UNITED STATES PATENT OFFICE.

FREDRICK ALFRED EDWARD JENKINS, OF SYDNEY, NEW SOUTH WALES, AUSTRALIA.

DIAPHRAGM FOR SOUND REPRODUCTION.

Application filed March 27, 1924. Serial No. 702,466.

To all whom it may concern:

Be it known that FREDRICK ALFRED EDWARD JENKINS, a subject of the King of Great Britain and Ireland, residing at 5 Haig Avenue, Summer Hill, Sydney, in the State of New South Wales, Commonwealth of Australia, engineer, has invented certain new and useful Improvements in Diaphragms for Sound Reproduction, of which 10 the following is a specification.

This invention relates to the construction of diaphragms for sound reproduction such as those used in talking machines and such instruments and the object of the invention 15 is to provide a diaphragm of uniform thickness and tension which will give a clearer and more natural reproduction of sound than any other diaphragm at present in use and which will not be effected by climatic 20 changes and which will not shatter under continued vibration.

A further object is to provide a diaphragm which will not set up any sound of itself when vibrated and which will be free 25 from any false vibration, but will truly and effectively reproduce the vibrations transmitted to it.

The invention comprises a tympan or membrane, a metal ring adapted to grip this 30 membrane evenly and subject it to uniform tension, and a resilient compound moulded round the ring to form a coating thereon to insulate the metal ring and membrane from the sound box.

35 The tympan or membrane is constructed of a plurality of very thin discs or sheets of suitable wood having, if desired, intermediate layers of light silk or similar material.

40 These sheets and layers are superimposed in such a manner that the grain or warp of no two sheets or layers is parallel and are rendered water proof and cemented or glued together under pressure to form a tympan or membrane of uniform thickness, strength 45 and resiliency in every direction.

The trimmed membrane is then placed within a metal ring of L section so that it is retained by the horizontal member of the 50 L. The vertical member is then hammered inwards to grip the membrane between the jaws of a ring of U section.

55 The ring is then caused to grip the membrane tightly and uniformly and is expanded outwardly to exert a uniform tension in all directions on the tympan. The ring also

prevents warping or twisting of the membrane.

In order to insulate the metal ring surrounding the tympan or diaphragm and provide a resilient seating for same within the sound box an enveloping ring of rubber or rubber compound or other resilient compound such as a mixture of glycerine and gelatine is moulded round the ring and is 60 allowed to encroach slightly on the membrane to prevent the vibration from extending to the metal ring.

In the drawings which illustrate a method of constructing a diaphragm according to 70 this invention,

Figure 1 is a diagrammatic elevation of a press for building up the membrane.

Figure 2 is a diagrammatic plan of same.

Figure 3 is a sectional elevation showing 75 the membrane placed in the retaining ring of L section.

Figure 4 shows the complete membrane and ring.

Figure 5 is a sectional elevation of a 80 mould for placing the resilient sound insulating material round the ring, and

Figure 6 is a sectional elevation of the complete improved diaphragm.

Fig. 7 is a plan view of the diaphragm 85 partly in section and before the resilient ring has been placed on the same.

The membrane or tympan 7 is built up of a plurality of layers 8 of wood reduced to the thickness of fine paper with or without 90 intermediate layers of fine silk or a similar material superposed on the lower member 9 of a press in such a manner that the grain or warp of no two layers is parallel. For example if it is considered that six layers of 95 material are necessary for a particular membrane the grain or warp of the first would be along the line A A and the second would be along the line B B and so on till the sixth layer would have its grain or warp along 100 the line F F, see Figure 2.

The layer or sheets are glued or cemented together under pressure between the members 9 and 10 of the press. The complete membrane is also rendered impervious to 105 moisture by any well known means either before being built up or when completed.

After being cut and trimmed to the desired size the membrane 7 is placed in the ring 11 as shown in Figure 3 so that it is supported by the horizontal member of the L. The vertical member is then turned

downwards to clamp the membrane as shown in Fig. 4, and is at the same time expanded in any common manner to evenly tension the membrane.

- 5 The ring and membrane are then placed in a mould 12 as shown in Figure 5 so shaped that the resilient covering 13 round the ring 11 may be poured into position. The ring 11 is entirely enclosed within this composition which extends slightly over the membrane as at 14 in Figure 6.

The resilient covering 13 may be of any suitable material such as rubber or rubber composition but is preferably a mixture of 15 glycerine and gelatine in the proportions of 3 parts glycerine to one part of gelatine or of equal parts of each.

I claim:—

1. An improved complete diaphragm for 20 sound reproduction comprising a membrane including several superposed water-proof, thin sheets of wood, the grain of each sheet being arranged at angles to the grain of the other sheets and the grain of all the sheets 25 being parallel to lines radiating at equal in-

tervals from a common point, a metal ring of U-section gripping the edge portion of the membrane and holding it taut, and a ring of resilient material formed around said metal ring and encroaching slightly on 30 said membrane.

2. In a diaphragm for sound reproduction, a membrane including several superposed water-proofed thin layers of wood, the grain of each layer being arranged at angles to the grain of the other layers and the grain of the layers being parallel to lines radiating at equal intervals from a common point, a metal ring of U-section gripping the peripheral edge portion of the membrane and holding it taut, and a resilient ring arranged around and entirely enclosing said metal ring, said resilient ring being formed of a 35 solid composition of gelatine and glycerine.

In testimony whereof he has affixed his signature in presence of two witnesses.

FREDRICK ALFRED EDWARD JENKINS.
